[57] CLAIM

The ornamental design for a surfboard having a water jet drive, as shown and described.

DESCRIPTION

FIG. 1 is a left side elevational view of a surfboard having a water jet drive showing my new design, the right side elevational view being a mirror image of that shown;

FIG. 2 is a top plan view thereof;

FIG. 3 is a bottom plan view thereof;

FIG. 4 is a rear elevational view thereof;

FIG. 5 is a front elevational view thereof; and,

FIG. 6 is a top, left, and front perspective view thereof,
the broken lines are for illustrative purposes only.

FIG. 1

FIG. 2

FIG. 5

FIG. 3

FIG. 4

FIG. 6
